UNITED STATES PATENT OFFICE.

EUGENE C. HELWIG, OF HACKENSACK, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed July 15, 1921. Serial No. 484,880.

To all whom it may concern:

Be it known that I, EUGENE C. HELWIG, a citizen of the United States, residing at Hackensack, in the county of Bergen, State of New Jersey, have invented certain new and useful Improvements in Telephone-Exchange Systems, of which the following is a full, clear, concise, and exact description.

This invention relates to telephone systems and more particularly to cord circuits therefor of the so-called universal type; that is, cord circuits which automatically adapt themselves to the character of the lines upon the mere insertion of the plugs into the spring jacks of such lines.

The object of this invention is to provide a cord circuit for use at positions where in addition to handling common battery and local battery manual lines, the operators control automatic switches to select common battery automatic lines using the same cords as are used for the common battery manual and local battery manual or magneto lines.

In accordance with the invention, the cords are provided with a pair of battery feeding bridges containing supervisory relays controlling supervisory lamps and also with a pair of bridges containing relays adapted to be operated by the magnetos of the magneto stations to control the same lamps. A dial is also provided and is automatically associated with the cord taken for use. This dial controls the automatic switches to extend connection to the common battery automatic lines. Current for talking purposes is fed to such lines, when called, from the connector in the well known manner. The response of the called party causes the connector to reverse the current flow in the cord to operate the polarized relay to control the calling supervisory lamp. The operation of this polarized relay also causes a reversal in the current flow in the calling line to operate the meter thereof, so that in the case of a call to an automatic line, the operator is relieved of the work of registering the call.

Referring to the drawings, Figs. 1 and 2 taken together illustrate a circuit arrangement embodying the invention.

A designates a common battery substation, B a magneto substation, and C an automatic substation. The subscriber at substation A, initiates a call by merely removing his receiver which causes the operation of

the line relay 101 to light the lamp 102 before the operator. The subscriber at substation B must actuate his call generator 103 to secure the attention of the operator by actuating the annunciator or drop 154. The subscriber at substation C must actuate his calling dial 105 to set selector brushes 106 upon a level of trunks 107, terminating in jacks 169 before the operator. The selection of one of these trunks causes the lamp 108 to light.

With this preliminary description, it is believed the invention will be most readily understood from a description of the operation, and considering first a call from the common battery substation A to the similar substation D, Fig. 2, the operator in response to the lighting of the lamp 102 inserts the plug 109 of the cord into the jack 110, which causes cut-off relay 111 to operate to deenergize the line relay 101, which in releasing extinguishes the lamp 102 in the well known manner. The circuit for the cut-off relay 111 includes a marginal relay 112 and a relay 113. The relay 112 operates only when the plug is inserted into the jacks 110 and 169 of the common battery lines, but the relay 113 operates when the plug is inserted into jacks associated with either common battery or magneto lines. Relay 113 in attracting its upper armature disconnects the busy test conductor 113 leading to the operator's telephone set, and completes the continuity of the tip conductor of the cord. At its lower armature, relay 113 prepares a circuit for the answering supervisory lamp 114, which lamp is not, however, lighted at this time due to its being shunted by a circuit that will be described. Relay 112 in operating closes the following circuit for feeding talking current to the calling substation: free pole of battery, relay 115, inner left armature and front contact of relay 112, lower winding of impedance coil 116, normal contact 117 of relay 118, conductor 119, lower left winding of repeating coil 120, lower talking conductor of the cord, normal contact 121 of relay 122, ring of the plug 109, ring of the jack 110, through the substation equipment returning over the tip conductor, tip of the jack, tip of the plug, upper talking conductor of the cord including alternate contact 123 of relay 113, and normal contact 124 of relay 122, upper left winding of repeat-

- ing coil 120, conductor 125, normal contact 126 of relay 118, conductor 127, upper winding of the impedance coil 116, inner right armature and alternate contact of relay 112 to ground. The operator upon inserting the plug, also actuates her listening key 200 to connect her telephone set (not shown) across the cord. The answering supervisory lamp 114 is now shunted over the following path: free pole of battery, outer left armature and alternate contact of relay 128 which operates due to the operation of relay 112, conductor 129, resistance 130, conductor 131, inner right armature and alternate contact of relay 128, armature and alternate contact of relay 115, conductors 132, 201, alternate contact 202 of the listening key 200, conductors 203, 133, relay 134 to ground. Relay 134 in attracting its right armature locks itself over the following path: ground, relay 134, its right armature and alternate contact, conductor 135, inner left armature and contact of relay 128, conductor 136, armature and alternate contact of relay 115, inner right armature and alternate contact of relay 128, conductor 131, resistance 130, conductor 129 through left armature and alternate contact of relay 128 to battery. This locking circuit is independent of the operator's listening key 200, and consequently remains closed after the listening key is restored. The operator now secures from the calling subscriber the number of the wanted line, and assuming that the calling subscriber desires to talk with the subscriber at station D, inserts the calling plug 204 in the jack 205 of said line, operating the cut-off relay 206 and marginal relay 207 and relay 208. Relay 207 operates only when the plug 204 is inserted in the jacks of common battery lines and does not operate when the plug is inserted into the jacks 209 of magneto lines, or jacks 210 of automatic common battery lines. Relay 207 closes the following circuit for feeding talking current to the substation D: ground, inner left armature and alternate contact of relay 207, conductors 211, 137, upper winding of the impedance coil 138, upper right winding of the repeating coil 120, tip conductor of the cord, normal contact 212 of the ringing key 213, normal contact 214 of relay 215, alternate contact 216 of relay 217, which relay operated when relay 208 operated and opened the test conductor 219, tip of the jack, through the substation apparatus, ring of the jack, ring of the plug, normal contact 220 of relay 215, normal contact 221 of the ringing key 213, lower talking conductor of the cord, lower right winding of the repeating coil 120, lower winding of the impedance coil 138, conductors 139, 222, inner right armature and alternate contact of relay 207, relay 223, conductor 239, contact 224 to free pole to battery. The operator now actuates her ringing key 213, impressing ringing current from generator 225 on the called line. Upon the response of the called party, talking current is fed over the path traced to the called substation. 70
- Upon the replacing of the receiver by the calling party, the answering supervisory lamp 114 is lighted over the following circuit: free pole of battery, outer left armature and alternate contact of relay 128, conductor 129, resistance 130, lamp 114, conductor 142, lower armature and contact of relay 113 to ground. The shunt about lamp 114 was opened due to the release of relay 115 when the calling party replaced his receiver. The replacing of the receiver by the called party lights the called supervisory lamp 226 over the following circuit: free pole of battery, outer right armature of relay 207, armature and normal contact of relay 223, conductor 270, resistance 227, lamp 226, lower armature and contact of relay 217 to ground. The operator withdraws the plugs from the jacks, the withdrawal of the plug 109 restoring the apparatus to normal. 80
- Common battery manual to local battery magneto.*
- In a call of this character the operations 95 are the same as those described up to the point where the operator inserts the plug into the jack 209 of magneto line E. This operates the cut-off relay 228 of the magneto line and relay 208. Marginal relay 207 remains inert due to the resistance of the cut-off relay 228. Relay 208, as before, operates relay 217 to cut off the busy test conductor 219 and complete the continuity of the tip conductor of the cord. Relay 207 remaining inert leaves the polarized relay 229 bridged across the cord circuit. The operator, by means of ringing key 213 now signals the subscriber at substation E. The transmitter of substation E is energized by the local battery 230, and the relay 207 in remaining inert maintains the common battery feed disconnected from the cord. 100
- When the subscriber at substation E actuates generator 231 to indicate to the operator that the conversation is concluded, the polarized relay 229 operates over the tip and ring conductors of the cord in series, lighting the lamp 226 over the following 105 circuit: free pole of battery, normal contact 224 of relay 235, conductor 239, relay 223, inner right armature and normal contact of relay 207, conductor 240, normal contact 234 of relay 235, conductor 233, alternate contact of relay 229, conductor 232, resistance 227, lamp 226 to ground on the lower armature and alternate contact of relay 217. Relay 223 in operating closes a locking circuit for the lamp 226, maintaining the same 110
- 115
- 120
- 125
- 130

lighted after the subscriber E ceases to turn his generator. This circuit is as follows: free pole of battery, contact 224, conductor 239, relay 223, inner right armature and 5 normal contact of relay 207, conductors 240, 236, normal contact 237 of the listening key, conductor 238, armature and alternate contact of relay 223, conductor 270, resistance 227, lamp 226 to ground at the lower 10 armature and alternate contact of relay 217. In response to the lighting of the lamp 226, the operator throws her listening key and challenges the called party and if no response is received, withdraws the plug 204 15 from the jack 209, which restores the apparatus to normal condition.

Common battery manual to common battery automatic.

20 A call of this character requires the same operations as that traced up to the point where the operator inserts the plug 204 into the jack 210, this jack terminating in an incoming selector at the automatic exchange 25 the brushes 241 only thereof are shown. As in the case of the magneto call, marginal relay 207 remains inert, and relays 208 and 242 operate. Relay 208, as before, operates relay 217. Relay 207 in remaining inert 30 maintains the polarized relay 229 across the cord and holds open the battery feeding bridge. Talking current for the called substation F will be fed from the connector in the well known manner over the windings 35 of relay 243.

The operator now turns the dial 244 for the first digit of the wanted number to set the selector 241 to the desired level, whereupon it automatically picks out a second 40 selector, the brushes 245 only whereof are shown, which selector will be set by the dial. As the dial moves off normal for the first digit it closes contact 246 to operate relay 247. Relay 247 closes the following circuit: 45 for operating relay 215: free pole of battery, relay 215, conductor 248, inner left armature of relay 235, conductors 249, 143, outer right armature and back contact of relay 144, conductors 145, 250, alternate contact 50 251 of key 200, conductor 252, inner right armature and alternate contact of relay 247, conductor 258 to ground at the armature and normal contact of relay 253. Relay 215 locks itself over the following circuit: 55 free pole of battery, relay 215, its alternate contact 254, conductor 255, normal contact of polarized relay 256, outer right-hand contact of relay 257, relay 253 to ground. Relay 253 in attracting its armature 60 removes ground from the conductor 258, thus preventing the dial from being associated with another cord circuit as long as relay 253 is operated. Relay 215 in attracting its armature 259 operates relay 235, 65 which in attracting its inner right arm-

ture locks itself to ground at the lower armature and contact of relay 217. The impulse relay of the incoming selector 241 operates as soon as the operator inserts the plug into the jack to prepare the circuit of 70 this selector. This circuit includes the tip of the jack 210, tip of the plug 204, contacts 216, contacts 214, 212, upper right-hand winding of repeating coil 120, upper winding of impedance coil 138, conductors 75 137, 211, outer left armature and back contact of relay 207, relay 229, conductor 222, conductor 139, lower winding of impedance coil 138, lower right winding of repeating coil 120, lower talking conductor, 80 contacts 221, 220, lower talking conductor to the ring of the plug.

As soon as the dial is moved off normal, and relay 215 is operated, the impulse contact 260 is substituted for the bridge just 85 traced. This circuit may be traced from the upper talking conductor, upper contact 261 of relay 215, conductor 265, outer left armature and alternate contact of relay 247, impulse contact 260, conductor 263, alternate contact 264 of relay 215, to the lower talking conductor. The dial in returning to normal position interrupts this bridge to set the incoming selector 241, whereupon it automatically hunts for and seizes a second selector 245. When the dial reaches its 90 normal position and releases relay 247, a bridge including polarized relay 256 is substituted for the bridge including only the impulse contact 260. This circuit may be 95 traced from contact 261, conductors 265, 266, relay 256, conductor 267, impulse contact 260, conductor 263, contact 264, this bridge preventing premature release. The operator now turns the dial for the next 100 digit to set the selector 245 to the level leading to connectors serving the group of lines containing substation F, whereupon this selector hunts for and seizes one of these connectors. As the dial is moved off normal, the relay 247 again operates to shunt out the relay 256 and leaves only impulse contact 260 across the loop leading to the automatic office. The operations involved in setting the connector for the tens and units digits 105 will not be described in detail since they are the same as those involved in setting the incoming selector and second selector. The connector tests the called line in the well known manner, and if found idle, applies 110 ringing current thereto to signal the called party.

Upon the removal of the receiver by the called party, relay 243 reverses the direction of current flow, thus operating polarized relay 256, which opens the locking circuit of relays 215 and 253. Relay 215 disconnects the dial and associated relays from the cord, and completes the talking circuit, and relay 253 in restoring renders the dial access- 115 120 125 130

sible to other cord circuits. Talking current is fed to the called substation from the connector and to the calling station over the path previously traced. If the called line is 5 busy, the connector transmits a busy signal back over the ring conductor to the operator's head set. This circuit includes the ring conductors of the connector and selectors, the rings of the jack and plug, the ring conductor of the cord, contact 264, conductor 263, contact 260, outer left armature and back contact of relay 247, condenser 275, conductor 276, to the head set. The operator then informs the calling party 10 that the line is busy or operates key 269 to release relay 215, allowing this busy tone to be transmitted to the calling line through the repeating coil 120. Upon the replacement of the receiver by the calling party 15 and the lighting of the lamp 114, the operator withdraws the plugs from the jacks, restoring the apparatus, including the automatic switches, to normal position. In case the call is successful, the replacement 20 of the receiver by the subscriber at substation F again reverses the direction of current flow in the cord, which causes the lamp 226 to light over the following circuit: free pole of battery, outer left armature and 25 alternate contact of relay 235, normal contact of relay 229, conductors 232, 270, resistance 227, lamp 226 to ground at the lower armature and contact of relay 217. If the operator actuates key 269 after she 30 has turned the dial for the last time, but before the dial has reached its normal position, this does not unlock relay 215 and 35 253, due to a circuit being closed for these relays at the outer right armature and alternate contact of relay 247, which remains 40 operated until the dial reaches its normal position. Relay 247 releases each time the dial reaches normal position and at its outer left armature connects the tone conductor 45 276 to the ring conductor of the cord so that tones on such conductor, if present, are transmitted to the operator between operations of the dial, as for example, if the incoming selector 241 or second selector 50 245 encounters a busy trunk group.

The response of the called party F in operating the polarized relay 229, actuates relay 118 (Fig. 1) to reverse the direction of current flow in the calling line to operate the meter 146 thereof, assuming that the calling station is a common battery automatic substation which is provided with a meter. This meter may be of the type shown in Patent No. 1,176,269 of March 21, 55 1916 to A. H. Blessing. The circuit for operating relay 118 is as follows: free pole of battery, relay 118, conductors 147, 271, alternate contact 272 of relay 235, conductor 233, alternate contact of relay 229, conductors 232, 270, resistance 227, lamp 226 to

ground at the lower armature and alternate contact of relay 217. Relay 118 in attracting its armature 148, locks itself to ground at the lower armature and alternate contact of relay 113. In attracting its 70 armatures 149 and 150, it reverses the direction of current flow in the calling line to operate the meter 146.

Magneto line to common battery line. 75

In a call of this character the marginal relay 112 does not operate when the plug 109 is inserted in the jack 151, and maintains the battery feed disconnected from the calling line, leaving a relay 152 adapted 80 to be operated by alternating current bridged across the cord. The relay 113, however, operates in series with the cut-off relay 153, the former relay disconnecting the busy test conductor 113 and completing 85 the continuity of the tip conductor of the cord, and the latter relay cutting off the drop 154 of the magneto line. The operator throws her listening key 200 and inquires the number of the desired line, and 90 extends the connection to line D, E or F as already described.

Upon the termination of the conversation, the subscriber at substation B operates his generator 103, which energizes relay 95 152. Relay 152 closes a circuit to operate relay 115 as follows: free pole of battery, relay 115, inner left armature and back contact of relay 112, armature and alternate contact of relay 152, outer left armature 100 and normal contact of relay 128, conductor 129, resistance 130, lamp 114, conductor 142, to ground at the lower armature and alternate contact of relay 113. Relay 115 in operating locks itself over the following circuit to maintain the lamp 114 lighted after the party at substation B ceases to turn generator 103: free pole of battery, relay 115, inner left armature and back contact 105 of relay 112, conductors 155, 273, normal contact 274 of key 200, conductors 201, 132, 136, armature and alternate contact of relay 115, conductor 156, outer left armature and normal contact of relay 128, conductor 129, 110 resistance 130, lamp 114, conductor 142, to ground at the lower armature and alternate contact of relay 113. The operator in response to the lighting of lamp 114 actuates listening key 200, which extinguishes the lamp, and challenges the calling party, 115 and if no response is received, removes the plugs 109 and 204 from their jacks, which restores the apparatus to normal condition.

The cord circuit is provided with a pair of keys RK, OK for impressing positive or negative high potential current on the sub-stations provided with coin boxes 159. These coin boxes may be of the type shown in Patent No. 1,043,219, Nov. 5, 1912 to O. F. Forsberg. If the coins are to be col- 120 125 130

lected, the operator actuates collect key CK. The closure of contact 160 operates relay 122, and the closure of contact 161 applies high potential positive current to the tip 5 and ring of the cord by way of the armatures of relay 122 to ground through the polarized magnet of the coin boxes 159 in the well known manner, this magnet operating to collect the coins. The closure of contact 163 of the key operates relay 118 which at its armature 148 locks up to the lower armature and alternate contact of relay 113, and in attracting its armature 164 prepares a circuit for lighting the coin pilot 10 lamp 165, this circuit being closed by a relay 162 which operates in series with the coin collect current if the coins have been deposited. If no coins were deposited, no ground would be present at the substation 15 as described in said Forsberg patent, and this relay would remain inert and lamp 165 would not light, thus notifying the operator that no coins were deposited. If the substation such as C is provided with a meter 20 146 instead of a coin box, as in station A, and the called line is either a line such as D or E, and the call is successful, the operation of the collect key CK operates the relay 118, as described, which reverses the current flow in the calling line to operate the meter of such line in the well known manner. If the coin or coins are to be refunded, the operator actuates refund key 25 RK, which operates relay 122 over contact 166, and the closure of contact 167 impresses high potential negative current on the tip and ring of the line by way of the armatures and front contacts of relay 122 to the polarized magnet in the coin box 159, 30 which magnet refunds the coins to the subscriber. The coin pilot lamp 165 operates due to the operation of relay 168 in the coin current circuit. Lamp 170 is the register pilot lamp and is operated when the reversing relay 118 operates to operate the calling line meter. It supervises the operation of 35 this reversing relay.

Relays 172, 173, interrupter 174 and bell 50 175 are provided to furnish a recall signal for lines such as A and C. The calling party desiring to resign the operator for any reason moves his switchhook up and down. The first interruption of the line circuit releases relay 115 which releases relay 134. When 115 again energizes, relay 55 134 in its retracted position operates relay 172 over a circuit including the retracted armature of relay 173, right winding of relay 172, resistance 176, left retracted armature of relay 134, outer right attracted armature of relay 128, conductors 177, 273, 60 contact 274 of key 200, conductors 201, 132, 136, attracted armature of relay 115, inner right attracted armature of relay 128, conductor 131, resistance 130, outer left at-

tracted armature of relay 128 to battery. Relay 172 in attracting its armature connects the interrupter to its left winding in series with relay 173 and when a metallic segment is reached it holds relay 172 operated through its left winding and operates relay 173 which opens the shunt about lamp 114. When the next insulated segment is reached relay 173 falls back again closing the shunt to again put out the lamp 70 and operate relay 172 preparing a circuit for the next metallic segment. Thus the lamp flashes to attract the attention of the operator. An audible signal in the form of a single tap bell 175 is also provided which 75 is tapped each time relay 173 operates.

What is claimed is:

1. In a telephone system, the combination with common battery manual lines terminating in jacks, local battery magneto lines terminating in jacks, common battery automatic lines, and operator's position, automatic switches, the first of said switches terminating in a jack at said position, and a cord circuit having a dial associated therewith for controlling said switches to connect with said automatic lines, said cord circuit having a pair of battery feeding bridges and, a second pair of bridges containing alternating current relays, said cord circuit including means automatically operated upon the insertion of the plugs of the cord into the jacks for including certain of said bridges in said cord for adapting the cord to the character of the connected lines. 100

2. In a telephone system, the combination with common battery manual lines terminating in jacks, local battery magneto lines terminating in jacks, common battery automatic lines, an operator's position, automatic switches, the first of said switches terminating in a jack at said position, a cord circuit having a dial associated therewith for controlling said switches to connect with said automatic lines, said cord circuit having a pair of battery feeding bridges containing supervisory relays, a second pair of bridges containing alternating current relays, supervisory lamps controlled thereby, said cord circuit including means automatically operated upon the insertion of the plugs of the cord into the jacks, for including certain of said bridges in said cord for adapting the cord to the character of the connected lines. 110

3. In a telephone system, telephone lines, a cord circuit, automatic switches, a dial for controlling the same to connect with said lines, a key, a relay for connecting the dial to the cord, a circuit therefor closed when the cord is taken for use, a locking circuit for said relay, a contact therein, a relay adapted to open the same when the key is operated to unlock said relay to disconnect the dial from the cord, a shunt circuit about said 120 125 130

- contact, and a relay adapted to close the same when the dial is in an off-normal position.
4. In a telephone system, telephone lines, a trunk line terminating in an automatic switch, a cord circuit for interconnecting said lines, a dial associated with said cord circuit for controlling said switch, a relay for connecting the dial with the cord, operated when the dial is moved off normal, a locking circuit for said relay including contacts of a second relay, an energizing circuit for said second relay controlled by a key, a shunt path around said contacts of the second relay controlled by a third relay, and an energizing circuit for said third relay closed while said dial is in an off-normal position.
5. In a telephone system, telephone lines, a trunks line terminating in an automatic switch, a cord circuit for interconnecting said lines, a dial associated with said cord circuit for controlling said switch, a relay for connecting the dial with the cord, operated when the dial is moved off normal, a locking circuit for said relay including contacts of a second relay, an energizing circuit for said second relay controlled by a key, whereby said locking circuit may be broken to disconnect said dial from the cord and means controlled by said dial for maintaining said locking circuit closed independent of said key.
6. In a telephone system, the combination with common battery manual lines and local battery magneto lines terminating in jacks, common battery automatic lines, an operator's position, automatic switches, the first of said automatic switches terminating in a jack at said position, and a cord circuit having a dial adapted to be associated therewith for controlling said switches to connect with said automatic lines, said cord circuit having means including a pair of marginal relays for automatically adapting the cord to the character of the connected lines upon the insertion of the plugs of the cord into the jacks.
7. In a telephone system, the combination with common battery manual lines and local battery manual lines terminating in jacks, local battery magneto lines terminating in jacks, common battery automatic lines, an operator's position, an automatic switch terminating in a jack at said position, and a cord circuit having a dial associated therewith for controlling said switch to connect with said automatic lines, said cord circuit having means including a pair of marginal relays and a pair of bridges including alternating current relays for automatically adapting the cord to the character of the connected lines upon the insertion of the plugs of the cord into the jacks.
8. In a telephone system, in combination, common battery manual lines, local battery magneto lines, common battery automatic lines, a cord circuit, and means in said cord circuit including a marginal relay and a bridge including an alternating current relay for automatically adapting the cord to extend a call from any one of said lines to any other of said lines.
9. In a telephone system, in combination, common battery manual lines, local battery magneto lines, common battery automatic lines, a cord circuit, a pair of battery feeding bridges, and a pair of marginal relays operatively associated with said cord upon the interconnection of certain of said lines and not upon the interconnection of other of said lines.
10. In a telephone system, a cord circuit, common battery manual lines, local battery magneto lines and common battery automatic lines adapted to be interconnected by said cord circuit, a first relay associated with one end of said cord circuit, a marginal relay in series with said first relay and means controlled by said marginal relay for adapting said cord circuit to operatively connect certain of said lines associated with said one end of the cord to any of said lines associated with the other end of said cord.
11. In a telephone system, a cord circuit, common battery manual lines, local battery magneto lines and common battery automatic lines adapted to be interconnected by said cord circuit, a polarized relay normally bridged across said cord, a marginal relay associated with said cord for removing said bridge from across said cord upon the connection of said cord with certain of said lines.

In witness whereof, I hereunto subscribe my name this 14th day of July, A. D. 1921.

EUGENE C. HELWIG.
